UNITED STATES PATENT OFFICE

JAMES R. HUGHES, OF SOUTH BEND, INDIANA, ASSIGNOR TO THE STUDEBAKER CORPORATION, OF SOUTH BEND, INDIANA, A CORPORATION OF NEW JERSEY

DOOR BUFFER

Application filed December 26, 1929. Serial No. 416,315.

This invention relates to buffers or cushioning devices designed for cushioning the door of vehicle bodies.

One of the objects is to provide a resilient cushioning member for cushioning the closing impact of the door and prevent rattling of the door for vehicle bodies when the same is in closed position.

Another object is to provide a device embodying a resilient cushioning member which may be conveniently attached to the door to effectively bear against a stationary part of the vehicle, such as a pillar therefor, to effect its function in the most satisfactory manner.

Another object is to provide a resilient buffer conforming in shape to that portion of the door to which it is attached and having a broad face inclined to the edge face of the door adapted to engage with a corresponding face on the body pillar to prevent the door from rattling and vibrating on its hinges when in closed position.

These being among the objects of the present invention, the same consists of certain details of construction and manufacture which will be apparent from the detailed description to follow, and then claimed, having the above and other objects in view.

In the accompanying drawings which illustrate a suitable embodiment of the present invention,

Figure 1 is a side elevation of an automobile, in dotted lines, showing the doors therefor in full lines.

Figure 2 is an enlarged transverse sectional view taken on the line 2-2 of Figure 1, showing my improved buffers attached to the doors.

Figure 3 is a perspective view of the buffer.

Figure 4 is a fragmentary elevational view of the body pillar.

Heretofore it has been the practice to use resilient buffers attached to the body pillar or the door in such a manner that they would cushion the closing impact of the door only but would not prevent rattling of the door due to movement of the same longitudinally to the axis of the vehicle body of which the door forms a part. In my improved device, I provide a door buffer which will cushion

the closing impact of the door and which will also effectively prevent rattling of the door when in closed position.

Referring to the accompanying parts of the drawings in which like numerals refer to like parts throughout the several views, I have shown a vehicle body 10, in dotted lines, in which is mounted the doors 11 and 12. As the construction of each door is the same, so far as this invention is concerned, except that the doors are shown as opening to the right and left, I will describe only one door in detail as the invention will be well understood therefrom. Each door comprises a sheet metal edge member 13 terminating in a flange 14 at its inner edge to receive the interior panel member 15. The edge member 13 terminates in a flange 16 at its outer edge to which is secured the outer panel 17, the panels 17 and 15 being formed to provide a recess in which the glass 18 is slidably mounted. The edge member 13 is formed to provide a recessed portion 19 into which the door buffer 20 is mounted. The door buffer 20 may be of a somewhat irregular shape adapted to conform with the shape of the recess 19 and the same is provided with a broad face 21 adapted to contact with a corresponding face on the body pillar. A reinforcing plate 22 is preferably moulded into the buffer 20 and is adapted to receive the screw 23 which may be inserted through the opening 24 formed in the buffer 20 and adapted to be screwed into the edge member 13, as clearly appears in Figure 2, to securely hold the buffer 20 in position.

Extending between the doors 11 and 12 is a body pillar 25 which preferably is provided with depressed portions 26 forming a face at an angle to the edge member 13 of the door and corresponding with the face 21 of the buffer 20. It will thus be seen that when the door is moved toward closed position that the face 21 of the buffer 20 will engage with the face 26 of the pillar 25 to cushion the closing impact of the door. It will also be understood that due to the fact that the face 21 of the buffer 20 is at an angle to the face of the edge member 13 of the door that the buffer 20 will prevent rattling or vibration of the

door due to any movement thereof in a direction parallel with the longitudinal axis of the body.

The door buffer heretofore described is very economical to manufacture, easy to assemble and furthermore it is easy to adjust the same relative to the fixed part of the body such as the pillar 25 and for that purpose, I preferably provide a shim or shims 27. As the door buffer becomes worn, the shims 27 may be positioned between the buffer 20 and the door member 13, as shown in Figure 2, so that any clearance or play between the buffer 20 and the pillar 25 may be taken up and the buffer will be caused to function in the most satisfactory manner. While I have shown only one shim 27 for accomplishing this purpose it, of course, is to be understood that any suitable number may be used or that the same may be dispensed with if the position of the buffer 20 does not require the use of the same.

I preferably form the buffer of a suitable resilient material for the purpose described and preferably use a moulded rubber, although the invention is not limited to the use of rubber for this purpose but instead any of the materials known to mechanics skilled in this art may be substituted which will accomplish the result heretofore described.

While I have shown one suitable embodiment of the present invention, it is to be understood that various modifications may be made without departing from the spirit and substance of this invention, the scope of which is commensurate with the appended claims.

What I claim is:

1. In combination with a door provided with an edge member having a recess formed therein and a body pillar having a recess at an angle to the edge face of said pillar in the region of the recess in said door, a resilient buffer having a metal plate formed therein and an opening substantially perpendicular to said plate, a screw insertable through said opening engageable with said plate for clamping said buffer in the recess in said door, said buffer having a broad flat face engageable with the angle face in said body pillar for cushioning said door and preventing longitudinal movement of the same relative to said pillar.
2. In combination with a door provided with an edge member having a recess formed therein, a body pillar having a depressed flat face substantially parallel with one of the walls of said recess, and a resilient buffer formed with a plurality of flat faces extending into said recess and secured therein and having a broad flat face exteriorly of said recess engageable with the depressed flat face of said pillar to cushion said door relative to said pillar.
3. In combination with a door provided with an edge member having a recess formed

therein, a wall portion of said recess being substantially perpendicular to the edge face of said door, a second portion being substantially parallel with said edge face, and a third portion being at an angle to said first named portions, a body pillar having a depressed flat face at an angle to the face of said edge member, and a resilient buffer having a portion extending into said recess engageable with the wall portions thereof and secured therein and having a broad flat face extending exteriorly of said recess engageable with the depressed flat face of said pillar to cushion said door relative to said pillar.

Signed by me at South Bend, Indiana, this 24th day of December, 1929.

JAMES R. HUGHES.
